FIREARM

Charles A. Young, Springfield, Ohio

Application July 17, 1947, Serial No. 761,648

1 Claim. (Cl. 42—70)

1

This invention pertains to firearms and more particularly to a safety lock for preventing accidental discharge thereof. It has long been usual to lock the firing hammer or other spring propelled impact member, or to lock the finger actuated trigger by which the firing hammer or impact member is released.

The present disclosure however differs therefrom by providing locking means for preventing the disengagement of the hammer engaging sear by which the firing hammer or impact member is ordinarily held in retracted or cocked condition, and the provision of unlocking means readily controlled by a part of the fingers of the shooter's trigger hand, other than his trigger finger, substantially at the moment of firing.

The object of the invention is to improve the structure as well as the means and mode of operation of safety fire control means whereby such safety mechanism will be simple in construction and may be economically manufactured and installed in conventional firearms, including existing firearms which will be efficient in use, automatic in operation, uniform in action, involving but few operative parts and be unlikely to get out of repair.

A further object of the invention is to provide conveniently positioned releasing means within easy grasp of the shooter at the moment of fire and operable without disturbing the shooter's aim.

A further object of the invention is to provide prevention of operation of the fire control mechanism substantially until the moment of the trigger retraction, and which will prevent release of the fire control mechanism in event the gun falls or received a violent shock.

The invention includes a safety fire control mechanism possessing the advantageous structural features and the inherent meritorious characteristics and mode of operation hereinafter set forth or their equivalents.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings or their equivalents.

In the drawings, wherein is shown the preferred, but obviously not necessarily the only form of embodiment thereof,

Fig. 1 is a side elevation of a conventional lock action of an ordinary gun with the housing side plate removed, to which the present safety lock is applied.

2

Fig. 2 is a plan view thereof.

Fig. 3 is a similar assembly embodying a different form of sear spring.

Like parts are indicated by similar characters of reference throughout the several views.

Referring to the drawings, 1 indicates the barrel or barrels of a conventional gun of which 2 is the usual stock and 3 the frame or housing interconnecting the barrel 1 with the stock 2 affording a mounting for the customary fire control mechanism.

Within the housing or frame 3 is a spring propelled firing hammer 4, or two such hammers in event the gun is of double barrel type, which are normally held retracted against the tension of their propelling spring by a sear 5 for each hammer. The sears are provided with notches 6 in which engage corresponding shoulders 7 on the hammers 4. In the drawings there are shown well known L-shaped sears 5 having rearwardly extended arms 8 which are overlaid by a spring plate 9.

On the under side of the housing or frame 3 is a trigger guard 10 within which are two finger operable triggers 11 of a double barrel gun. As thus far described the structure is that of a conventional firearm, which may be single fire or double fire gun, which, per se, forms no part of the present invention.

Projecting upwardly from the bottom of the frame or housing 3 is a standard 12 to the top of which is pivoted, for to and fro oscillatory motion, an arcuate arm or cam 13 having a projecting lug 14 which overlies and engages the spring plate 9 which in turn bears upon the rearwardly extending arms 8 of the sears 5 to lock the spring plate and with it the sears 5 against elevation. The arcuate arm 13 extends downwardly and rearwardly of the trigger guard 10, and is provided at its extremity with a gravity weight 15 assisted by a compression spring 16. Normally the weight portion 15 of the arm projects exteriorly of the frame or housing at the rear of the trigger guard, in which position the lug 14, upon the arcuate arm 13, overhangs and bears upon the spring plate 9 to prevent elevation of the sear arms 8 to disengage the notch 6 of the sear 5 from the shoulder 7 of the hammer 4, under influence of retraction of a trigger 11. The head 15 of the locking arm 13 normally projects in a position to be conveniently grasped by the fingers, other than the trigger finger, of the shooter's hand, while grasping the neck of the stock 2, with his trigger finger in firing position adjacent to a trigger 11. In such position, a slight squeeze of the shooter's hand about the neck of the gun stock, thus de-

pressing the head 15 of the locking lever 13, retracts the locking lug 14 from over the spring plate and sear arms, enabling the latter to be elevated to disengage the notch 6 of the sear from the shoulder 7 of the firing hammer 4, to discharge the firearm. Immediately upon release of the shooter's grasp, the locking lever 13 is immediately returned to locking position by the reaction of the spring 16.

Thus the sear is locked in engaging relation with the hammer at all times, until the moment of firing. The act of grasping the gun in firing position is sufficient to momentarily unlock the sear for disengagement from the hammer by retraction of a trigger 11. The structure obviates the safety locks to be manually released in advance of positioning the gun, thus leaving the firearm without safety protection until again manually returned to operative relation.

As shown in the drawings the spring plate is bifurcated, each furcation of which overlies and yieldingly resists one sear independently of the other. In the assembly illustrated, the spring plate 9 is engaged and clamped in operative position by one of the studs vertically transfixing the frame or housing 3. However, in other forms of assembly wherein, for example an expansion spring 18 is used as in Fig. 3, the locking lever 13 may engage directly with the sear arms 8 instead of indirectly through the interposed spring plate 9. Obviously the present safety lock is applicable to sears of other shapes and motion. The assembly shown in the drawings is for illustrative purpose only, and the invention is not limited to the specific arrangement shown.

The present construction is such that immediately upon release of the head 15 of the locking lever 13 by the hand of the shooter, the lug 14 is at once automatically presented in sear locking position. The gun is then prevented from discharge, even though the gun is dropped or falls down. In event that one barrel only of a double barrel gun is discharged while the locking lever head 15 is held depressed, immediately upon release of grasp on the gun stock and the head 15 of the locking lever, the lug 14 instantly locks both sears. However this in no way interferes with the opening of the gun and ejection

of the discharged shell, and after reloading the gun may be again closed without danger of accidental discharge.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claim.

Having thus described my invention, I claim:

25 A safety lock for a multi-barreled firearm wherein a plurality of sears are held in engagement with associated impact members to hold the latter cocked and are disengaged by retraction of an associated trigger, including a single 30 spring influenced depressible cam member normally overlying the sears and preventing disengagement of a sear from its associated impact member of the firearm and depressible by grasp of the shooter's hand while positioned for retraction of the trigger to temporarily unlock the sears for disengagement by trigger operation.

CHARLES A. YOUNG.
